UNITED STATES PATENT OFFICE

103,694

DESIGN FOR A DISPLAY STAND OR SIMILAR ARTICLE

Maurice J. Schless, New York, N. Y.

Application January 6, 1937, Serial No. 66,930

Term of patent 14 years

To all whom it may concern:

Be it known that I, Maurice J. Schless, a citizen of the United States, residing at New York, in the county of New York and State of New York, have invented a new, original, and ornamental Design for a Display Stand or Similar Article, of which the following is a specification, reference being had to the accompanying drawing, forming a part thereof.

I claim:

The ornamental design for a display stand or similar article, as shown.

MAURICE J. SCHLESS.
